(57) **CLAIM**

The ornamental design for a wall mounted electronic device holder, as shown and described.

DESCRIPTION

FIG. 1 is a front perspective view of the wall mounted electronic device holder showing my new design;

FIG. 2 is a front perspective view thereof, holding an electronic device;

FIG. 3 is a front elevation view thereof;

FIG. 4 is a rear elevation view thereof;

FIG. 5 is a bottom plan view thereof;

FIG. 6 is a top plan view thereof;

FIG. 7 is a right side view thereof; and,

FIG. 8 is a left side view thereof.

Broken lines are included for depicting environmental subject matter and form no part of the claimed design.
